United States Patent Office.

CHARLES H. CHILDS, OF CLEVELAND, OHIO.

Letters Patent No. 78,185, dated May 26, 1868.

IMPROVED GAS-APPARATUS.

The Schedule referred to in these Letters Patent and making part of the same.

TO ALL WHOM IT MAY CONCERN:

Be it known that I, CHARLES H. CHILDS, of Cleveland, in the county of Cuyahoga, and State of Ohio, have invented certain new and useful Improvements in a Gas-Apparatus; and I do hereby declare that the following is a full and complete description of the same, reference being had to the accompanying drawings making part of this specification, in which—

Figure 1 is a side view of the apparatus.

Figure 2 is a top view of the inside.

Figure 3 is a view of the under side of the receiver.

Figure 4, a vertical transverse section.

Like letters of reference refer to like parts in the different views.

In fig. 1, A is a metallic case, the size of which being according to the capacity of the machine required. Within this case, and secured to the bottom of the same, is a lining or cylinder, B, the diameter of which, being much smaller than that of the case, leaves an annular space or chamber, C, between the walls of the two, and in which is fitted a float or meter-cover, D. Within this cylinder is fitted the air-chamber E, a top view of which, and an inside view of the bottom, is shown in fig. 2. This chamber is constructed with an inner and outer wall, making a wide annular space, F, between them, which, it will be seen, does not reach to the bottom of the case A, but stops at the diaphragm G, which forms the bottom of the air-chamber E.

The outer wall of the chamber continues down to near the bottom of the case, dividing the lower part into a section or chamber, G'.

The chamber E is put in communication with the lower part, G', by means of tubes, H, fig. 2, also indicated by the dotted line a in fig. 4.

These tubes are constructed of perforated sheet metal, and are wrapped in cotton wicking, or with other like textile or flocculent material, I; also ropes, of the same material, are drawn around and through the tubes, with their upper ends projecting above the diaphragm, as shown at J, fig. 4. The position of these tubes, with their covering and filling, is also shown in fig. 3, which represents the bottom of the chambers E F.

Leading from the outside of the case A to the chamber E is an air-pipe, M, which, it will be seen, passes under and through the bottom of the case, and terminates in one of the tubes H, referred to.

N is an eduction-gas pipe, leading from the lower section, G', to the outside of the case, from thence to the burner.

Having thus described the construction and arrangement of the apparatus, the practical operation of the same is as follows:

The air-chamber E, when the apparatus is together, as shown in fig. 1, is charged with air, by raising up the float or cover D, which causes a vacuum to form in the chamber. The air is allowed to pass into the chamber by turning the stop-cock O, which on being fully filled is then closed. The annular chamber F is charged with naphtha, gasoline, or with any of the products of the distillation of petroleum. From this chamber it is allowed to flow into the lower section, G', so as to cover the bottom for a few inches in depth.

The textile materials being partially immersed in the fluid, soon become saturated therewith, and thus the gaseous and volatile elements of the fluid are evolved, and disseminated above the bulk of the fluid.

The gas thus evolved, and the inducted air, are prevented from escaping by the space G, between the outside case, A, and cylinder or lining B, being filled with water, and in which the float is immersed.

Now, as the float is forced down, by weights being placed upon it, or by any other mechanical appliance, the air is forced from the chamber E, through the tubes H, into the section G' below, where it becomes charged with the gases eliminated from the fluid.

The air thus treated becomes highly illuminous, and escapes from the apparatus through the pipe N to the burner, as before said.

What I claim as my improvement, and desire to secure by Letters Patent, is—

1. The perforated tubes H, surrounded with textile or fibrous material, and chamber G', in combination with the chamber E and annular space F, substantially as and for the purpose specified.

2. The pipes M N and chamber G', in combination with the diaphragm G, annular chambers C. and cover D, arranged as and for the purpose set forth.
